DRAFT MECHANISM

John S. McPherson, Columbus, Ohio, assignor to
 The Buckeye Steel Castings Company, Columbus, Ohio

Application November 9, 1931, Serial No. 574,005

4 Claims. (Cl. 213—7)

This invention relates to improvements in draft mechanism for railway freight cars.

Due to the increase in capacity of freight cars and the increase in length of freight trains, a limit is being approached where the present types of friction draft gears are inadequate to perform the function for which they are intended. The space provided for the draft gear in the present day freight cars is limited in so far as the width and depth is concerned. Provision can be made, however, to increase the length of the gear and its travel, or to use two gears applied in series.

My invention is related to the latter type, and one of the objects of the invention is to provide a construction adapted for use with tandem gears.

Another object is to provide such mechanism in which the slots for the horizontal key are much longer than those ordinarily employed, to accommodate the tandem gears, and in accordance with the present invention, the striker arranged at the outer end of the draft device is elongated rearwardly and provided with special slots for the horizontal key.

Another object is to furnish mechanism of this character, in which the carrier for the coupler shank has a narrow coupler bearing and a wide seat on the striker; the narrow coupler bearing providing clearance for projections at the front and rear end of the shank.

A further object is to provide a novel form of thimble adapted to be placed between the two gears; such thimble moving rearwardly with the gears on buff and functioning as a stop for the rearmost gear during pull.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a top plan view partly in horizontal section of my improved mechanism with the draft gears eliminated to facilitate illustration.

Fig. 2 is a longitudinal vertical sectional view of the same with the front draft gear omitted and the rear one shown in dot and dash lines.

Fig. 3 is a front end view partly in transverse vertical section; the section being taken on the line 3—3 of Fig. 2.

Referring to the drawings, 1 designates the coupler and 2 the yoke, which in the construction illustrated, are connected by a vertical swivel pin 3. However, in so far as the general arrange-

ment is concerned, the ordinary rigid shank coupler and horizontal keyed vertical cast steel yoke can be used.

The striker 4 in the present instance has cast integral with it the front draft lugs 5 which are slotted or spaced apart between their upper and lower ends, by slots 6 for the application of the horizontal key 7. Due to the double travel of the key in buff, the slots must be long enough to provide clearance for the key, making it necessary to cut through the follower bearing faces 8 of the front draft lugs. However, in order to tie the top and bottom portions of the front lugs together, U-shaped members or portions 9 which extend rearwardly, are cast integral with the draft lugs 5. In other words, the members 9 are integral with the striker, and they provide slot portions rearwardly of the front draft lugs to receive the key 7. Heretofore, the slots equivalent to the ones 6, were placed entirely in front 20 of the rear faces 8 of the front draft lugs.

The striker 4 is shown with a separate type of carrier 10. This, however, is optional, depending on the type of coupler and yoke used, and whether a tie under the carrier and integral with the striker, is desired. With the swivel type coupler, it is necessary to use a removable carrier iron as shown. In accordance with my invention, this carrier is so designed that clearance is provided in the pull direction for the bottom lugs 11 on the 30 coupler shank 1, and the bottom of the coupler head 12 in the buff direction. With regard to this, it will be observed that the top portion of the carrier is recessed at the rear, as shown at 10a, and this makes the upper portion of the 35 carrier just about half as thick as the lower portion of the same. This necessitates a narrower coupler bearing 13 than is usual practice, but in order to obtain the desired stability, the lower part of the carrier is widened out where it seats 40 on the supporting lugs 14 which are integral with the striker. In order to provide clearance for the usual carrier bolt 15, it will be noted that the supporting lugs or legs 14 are lowered to provide an extending foot 16 at each end of the carrier. 45

Another novel feature of the invention resides in the floating thimble or follower block 17 which straddles the yoke butt 18 from the rear, thereby allowing the two gears to act in series under buffing forces. At this point it will be noted that the 50 space 17a within the yoke will accommodate one draft gear while the other one 17b is arranged rearwardly of said thimble. Under buff conditions, the straps 19 and butt of the yoke are floating members. The lugs 20 of the cast thimble act 55

as rear follower stops for the front gear and transmit the forces through plate 19a to the rear gear 17b. Clearance "A" is provided so that the yoke butt can move back between the lugs 20 an 5 amount equal to the travel in buff of the front draft gear without contacting the front of the plate 19a of the thimble 17. In pull, pressure is removed from the front of the lugs 20, and in order to prevent forward movement of the thimble 17, the plate 19a is extended downwardly as at 19b so that it contacts the yoke carrier and tie plate 21 which serves as a support for the thimble, as well as for the rear end of the yoke. A stop 19c may also be arranged at the upper end of the 15 thimble if desired for limiting the forward movement of the thimble.

A special type of center casting and body bolster construction is employed with this novel draft mechanism. In the type illustrated, the 20 center casting 22, the center plate 23, and the bottom flange web of the body bolster construction 24 are all cast integral. Due to the long draft gear pocket extending near the body bolster center line, it is believed that the usual built-up construction would be considerably weakened, and for this reason, we have devised this special type 25 of center casting and body bolster construction. This casting has a bearing plate 29, and is also provided with rearwardly extending flanges 30 to receive the rivets 31 employed in connecting the casting to the center sills. It is tied together at the bottom by a plate portion 32 which extends beyond the point 33 at which the inturned flanges 34 of the center sills 35 are cut off. A flange 36 30 also ties the center casting 22 to the center plate 23, and also acts as a spacer and reinforcement for the sills 35. Such flange is stiffened by the rib 37.

The flanges 24 act as the bottom cover plate for 40 body bolster 28 to points between the usual side bearings and the center plate.

A carrier 38 for the rear draft gear is arranged just forwardly of the casting 22, and is secured to the outer flanges of the center sills.

To assemble this type of draft construction, the 45 rear draft gear 17b is first applied and held in place by the carrier 38. The yoke 2, with the front gear in position therein, is then raised between the sills 35, and the yoke and gear carrier 39 are applied. The thimble 17 is then positioned between the two draft gears and the carrier 21 is secured in position. The coupler shank 1, the swivel pin 3 and retainer, the horizontal key 7 and retainer, the coupler carrier 10 and bolt 15 are then applied in the order named. Of course, if desired, the swivel shank coupler, yoke, front gear and swivel pin may be assembled as a unit.

In operation, it will be understood that on pull, 60 the yoke butt 18 will act to compress the front draft gear between the front follower and said butt, and at such time, the front of the rear draft gear will simply be pressing against the plate 19a of the thimble, and the latter will not move forward, as it is halted by the carrier 21. On buff, however, the thimble is caused to move rearwardly, when the force is sufficient, and this will 65 act to compress the rear draft gear as well as the front one and has the effect of increasing the shock absorbing capacity of the draft mechanism in buff over that in pull, by an amount equal to the capacity of the rear draft gear. The arrangement may be modified by placing a "snubbed" 70 draft gear at the rear, that is, one that is held in

a state of partial compression, so that the rear draft gear will not function as a draft gear until the front one has been compressed a predetermined amount.

From the foregoing it is believed that the construction, operation and advantages of my invention may be readily understood by those skilled in the art, and I am aware that changes may be made in the details disclosed, without departing from the spirit of the invention, as expressed in 10 the claims.

What is claimed and desired to be secured by Letters Patent is:

1. In draft mechanism of the tandem gear type, spaced draft sills, a yoke, a one-piece thimble co- 15 operating with the yoke and forming lugs adapted to be engaged by the rear follower plate of the front draft gearing, a carrier positioned transversely of and attached to the sills for supporting the thimble for floating movement, said thimble 20 having a plate at its rear end adapted to abut against the front end of the rear draft gearing, and means including abutment surfaces on the plate of the thimble and carrier for limiting the forward movement of the thimble. 25

2. In draft mechanism of the tandem gear type, spaced draft sills, a yoke, a one-piece thimble co- 30 operating with the yoke and forming lugs adapted to be engaged by the rear follower plate of the front draft gearing, a carrier positioned transversely of and attached to the sills for supporting the thimble for floating movement, said thimble 35 having a plate at its rear end adapted to abut against the front end of the rear draft gearing, and means including abutment surfaces on the plate of the thimble and carrier for limiting the forward movement of the thimble, said carrier also supporting the rear end of said yoke.

3. In draft mechanism of the tandem gear type, spaced draft sills, a yoke, a one-piece thimble co- 40 operating with the yoke and forming lugs adapted to be engaged by the rear follower plate of the front draft gearing, a carrier positioned transversely of and attached to the sills for supporting the thimble for floating movement, said thimble 45 having a plate at its rear end adapted to abut against the front end of the rear draft gearing, and means including abutment surfaces on the plate of the thimble and carrier for limiting the forward movement of the thimble, said carrier being detachably connected to the draft sills and 50 also supporting the rear end of the yoke, whereby when the carrier is detached the yoke, thimble and front and rear draft gearing may be removed downwardly from between the draft sills. 55

4. In draft mechanism of the tandem gear type, spaced draft sills, a yoke, a one-piece thimble co- 60 operating with the yoke and forming lugs adapted to be engaged by the rear follower plate of the front draft gearing, said thimble and yoke being positioned between said sills, carrier irons detachably connected to the sills and supporting the yoke, thimble and front and rear draft gearing to permit the yoke, thimble and front and rear draft gearing to be removed downwardly from between the sills when the carrier irons are detached, said thimble extending from one sill to the other and 65 having a plate at its rear end adapted to abut against the front end of the rear draft gearing, and means including abutment surfaces on the plate of the thimble and one of said carrier irons for limiting the forward movement of the thimble. 70
